UNITED STATES PATENT OFFICE.

CHARLES THOMAS BROCK SANGSTER, OF BOURNBROOK, ENGLAND.

DESIGN FOR A BICYCLE-FRAME.

SPECIFICATION forming part of Design No. 34,257, dated March 19, 1901.

Application filed December 8, 1900. Serial No. 39,238. Term of patent 3½ years.

To all whom it may concern:

Be it known that I, CHARLES THOMAS BROCK SANGSTER, engineer, a subject of the Queen of Great Britain, residing at Componentsville, 5 Bourubrook, near the city of Birmingham, England, have invented a certain new and original Design for a Bicycle-Frame, of which the following is a specification.

The annexed drawing represents a frame 10 which is in accordance with my new design.

The leading or material feature of my said design consists in the crossed double-top stay *a*, one member *a'* of which proceeds from the seat-lug *b* diagonally downward and terminates in a lug *c'* at or near the bottom of the head *c*, while the other member *a''* starts from 15 a supplemental lug *b'* on the seat-tube *b* and

proceeds diagonally upward to a lug *c''* at or near the top of the head. At their intersecting or crossing point the stay members are 20 tied together by a four-branched lug, such as *d*.

Having described my invention, what I claim as new, and desire to secure by Letters Patent, is—

The design for a bicycle-frame as herein shown and described.

In testimony whereof I have hereunto set my hand in presence of two subscribing witnesses.

CHARLES THOMAS BROCK SANGSTER.
